UNITED STATES PATENT OFFICE.

JAMES M. WILSON, OF NEWARK, NEW JERSEY, ASSIGNOR TO SPLITDORF ELECTRICAL COMPANY, OF NEWARK, NEW JERSEY.

ELECTRIC GENERATOR.

1,219,520.

Specification of Letters Patent.

Patented Mar. 20, 1917.

Original application filed April 17, 1914, Serial No. 832,539. Divided and this application filed October 8, 1915. Serial No. 54,702.

To all whom it may concern:

Be it known that I, JAMES M. WILSON, a citizen of the United States, residing at Newark, in the county of Essex and State of New Jersey, have invented certain new and useful Improvements in Electric Generators, of which the following is a specification.

My invention relates to improvements in electric generators used for both ignition and lighting work in which the current for both uses is generated within the machine and delivered to the spark plugs or ignition devices of an internal combustion engine as well as to the lamps and battery of the vehicle to which the generator is attached.

This application is a division of my co-pending application, Serial No. 832,539, filed April 17, 1914, and has for one of its objects the development of a generator which is small and compact and suitable for the replacement of the magneto on a moving vehicle, particularly on a motorcycle. It is now customary to use electric lights on motorcycles, as well as on other moving vehicles and means must, therefore, be provided for furnishing current for the lights and charging the storage battery as well as to provide ignition current for the engine sparking devices. When a two cylinder engine is to be fired, a distributor is required as well as a timer which has an associated member that is adjustable for the purpose of advancing and retarding the spark.

Another object of my invention is to produce a single unit, having a direct current generating rotor driven by gearing or other suitable means from a rotatable member which controls the current to the engine ignition devices.

The size of my single unit is held to a minimum by driving the direct current rotor or armature at a speed somewhat greater than the timer rotatable member, so that the battery will begin to charge at a relatively low speed of the engine driving the unit.

Other and further objects of my invention will be apparent to anyone skilled in the art from a consideration of the drawings and specification, in which—

Figure 1 is a longitudinal section of my electric generator showing the timer rotatable member at the bottom and the direct current generating rotor or armature at the top.

Fig. 2 is a left hand end view of Fig. 1 having the timer box cover as well as the direct current cut-out box cover removed.

Fig. 3 is an elevation of the distributor, driven by the timer rotatable member, and

Fig. 4 is a side view of Fig. 3 with a portion of the distributor spool broken away to show the distributor segment.

Referring now particularly to the drawings in which like numerals refer to corresponding parts in the various figures, 1 is a base of non-magnetic material to which are attached in any suitable manner, pole pieces (not shown) in the sectional elevation of Fig. 1 which is taken between opposite poles.

Attached in any suitable manner to the said pole pieces and to base 1 are two main end plates 2 and 3. Fastened to the end plate 2 is a supplemental plate 55, which also carries an auxiliary plate 4. A bearing 5 is mounted in end plate 2 and a bearing 6 is mounted in supplemental plate 55. Attached to end bearing plate 3 is a housing member 7, which carries bearing 8. Another bearing 9 is carried by end plate 3. Supported between the bearings 6 and 9 is a rotatable member 10, which carries the usual high and low tension windings, indicated by 11. On one end of rotatable member 10 is a distributor 12 which is shown more in detail in Figs. 3 and 4. On the other end of the rotatable member 10 is a timer consisting of a plate 15 upon which is mechanically mounted a contact block 16 but which is insulated from the plate 15. Block 16 carries an adjustable contact 17 adapted to cooperate with a movable contact 18 carried by the breaker arm 19, pivoted to the pin 20, that is fastened to plate 15. 21 is a friction wearing element carried by breaker arm 19 and is adapted to engage the cams 13 and 14 that are attached to the cam holder 35. The primary winding of the rotatable member is connected in the usual manner to the two members 16 and 19 of the timer or circuit breaker. The operation of the primary through the timer is well understood and is not further described herein.

The inner end of the secondary winding of the rotatable member 10 is grounded to the frame of the machine and the open or free end is connected to the segment 22, which is usually molded into the insulating distributor ring 12. As shown in the draw-

ings, the distributor ring 12 is adapted for a two cylinder engine, two brushes 23 and 24 being used to collect the current from the segment 22 at a time determined by the operation of the timer and timing lever 35, it being understood that the lever 35 may be advanced or retarded according to requirement, so that the friction element 21 strikes the cams 13 and 14 sooner or later. The horn 36 of the collector spool 12 projects through the driving end plate 37 of the rotatable member 10 for the purpose of protecting or insulating the high tension lead from the driving end plate 37 which is securely fastened to the driving shaft 38. The brush holders used for supporting brushes 23 and 24 are mounted in any suitable manner on the end plate 3 but in the sectional view shown these brush holders do not appear. However, it is understood that suitable conductors lead from these brush holders to the igniters in the engine cylinders.

Above the timer and ignition rotatable member 10 and mounted on bearings 5 and 8 is a direct current generating rotor 47, having a commutator 39 inclosed within the housing 7. The brush holders are carried by the housing 7 in any suitable manner but in the sectional view do not appear. Covering the housing 7 and the brush holders to protect them from dirt and water is a cap 40. Keyed to the shaft extension 33 of the rotor 47 is a hub 34, which is rigidly fixed to the inner race of the radial bearing 5 so that the armature 47 may be readily removed without disturbing the gear 45, which is carried on the hub 34 or without disturbing the bearing 5. The hub 34 has a plate 46 integral or securely fastened thereto and this plate carries studs 48 to which are pivoted the weighted arms 25. Loosely mounted on the shaft extension 33 is a sleeve 30, which is moved back and forth by the weighted arms 25. Mounted in the end of the sleeve 30 is a ball 26, which runs against the friction wearing plate 27. This friction wearing plate 27 is attached to a movable spring 28, which carries a contact 29. Mounted in any suitable manner within the auxiliary plate 4 is a stationary member 31 that carries a contact 32. Members 25, 26, 30, 34, 46 and 48 constitute a centrifugal governor which operates in accordance to the speed of the rotor 47 to close and open contacts 29 and 32. It will be understood that various modifications relating to the governor and switch mechanisms just referred to are contemplated in my application previously referred to. Mounted on the timer and ignition member 10 is a gear 44, which is adapted to engage gear 45, so that when driving power is applied to shaft 38, the direct current rotor 47 is operated through the agency of the gears 44 and 45. These gears are so

chosen that the direct current rotor 47 is driven at a higher speed than the rotatable member 11. A cap 41 is used to cover the direct current switching mechanism and a cap 42 held in place by spring 43, is used to cover the circuit breaker or timer mechanism.

As previously stated it is necessary to regulate the amount of current delivered by the machine and one form for doing this is shown in Fig. 1 where an extension 49 of one of the pole pieces is shown projecting above the top of the rotor 47. A U shaped spring 50 is mounted on the extension 49 and the one opposite thereto (not shown) by screws 51. The top portion of the spring 50 carries a keeper 52, which spans the said pole extensions and is thereby acted on in accordance with the magnetic flux carried by them. An adjustment of the keeper 52 is provided by the screw 53 and lock nuts 54, so that the air gap between the keeper 52 and the pole extensions can be adjusted to meet the necessary operating conditions. My application hereinbefore referred to describes and claims this and other means for regulating the current and it will not be described further herein.

While I have shown a distributor for a two cylinder engine, it will be understood that a ring suitable for a four cylinder engine may be used, such changes in the end plate 3 being made to accommodate such a distributor ring.

Modifications of this character as well as others will be apparent to anyone skilled in the art and are believed to come within the spirit of the invention and the scope of the appended claims.

Having thus described my invention, what I claim is:

1. An electric generator, including in combination, a timer rotatable member, a direct current generating rotor and gearing connecting said timer rotatable member and the shaft of said rotor, whereby said rotor is driven at a higher rate of speed than said timer rotatable member, said parts forming a single unit.

2. An electric generator having in combination, a timer rotatable member, a direct current generating rotor, gearing connecting said timer rotatable member and the shaft of said rotor, whereby said rotor is driven at a higher rate of speed than said timer rotatable member and an adjustable timing device adapted to coöperate with said timer rotatable member for the purpose of producing electrical impulses at stated intervals.

3. An electric generator, including in combination, a rotatable member, ignition timing mechanism operated by one end of said rotatable member, the other end of said rotatable member adapted to receive suitable intervals.

driving means, bearings for supporting said rotatable member between said driving end and said ignition timing mechanism, a second shaft, bearings supporting said last named shaft at its end, and a generating rotor carried by said second shaft.

5. An electric ignition generator including in combination, a timer rotatable member, a generating rotor, geared to said timer rotatable member and driven thereby, and a distributor having its revolving part attached to said timer rotatable member and adapted to connect the ignition circuit successively with the various cylinders of an internal combustion engine.

10. An electric ignition generator, including the combination with a timer rotatable member, an adjustable timing member, a direct current generating rotor and bearings therefor, bearings for said rotatable mem-

ber, a support for said adjustable timing member and field windings disposed on opposite sides of said timer rotatable member.

15. An electric ignition generator, including the combination with a timer rotatable member, an adjustable timing member, a direct current generating rotor, bearings for said rotatable member and said rotor, an automatic switching device responsive to the speed of said rotor for controlling the current therefrom, commutator brushes and brush holders for collecting current from said rotor, a cover to protect said brush holders, a cover to protect said switching mechanism operated by said rotor, and a cover for protecting said timing mechanism.

20. In witness whereof, I affix my signature.

JAMES M. WILSON.
